US00D359506S

United States Patent [19]

Lee

[11] Patent Number: Des. 359,506

[45] Date of Patent: ** Jun. 20, 1995

[54] LASER PRINTER

[75] Inventor: Jae K. Lee, Seoul, Rep. of Korea

[73] Assignee: Samsung Electronics Co., Ltd.,
Kyunggi, Rep. of Korea

[**] Term: 14 Years

[21] Appl. No.: 18,002

[22] Filed: Jan. 26, 1994

[30] Foreign Application Priority Data

Sep. 2, 1993 [KR] Rep. of Korea 1993-17819

[52] U.S. Cl. D18/55

[58] Field of Search D18/50, 54-55;
400/690-694, 690.1-690.4, 613, 613.1-613.4
